UNITED STATES PATENT OFFICE.

MAXWELL H. SPREEN, OF DETROIT, MICHIGAN.

MECHANICAL REFRIGERATION.

Application filed March 8, 1926. Serial No. 93,004.

My invention relates to mechanical refrigeration, and is particularly applicable to mechanical refrigeration designed for cooling refrigerator cabinets of the household or store type, and the principal object of my invention is to provide a new and improved brine tank particularly adapted for use in such household and store refrigeration units, and to provide the increased contact surface between the brine tank and the circulatory air desirable in all such installations and particularly required in the larger installations where the surface of the brine tank reaches a relatively low ratio to the cubic contents of the tank.

In the drawings accompanying this specification and forming a part of this application I have shown, for purposes of illustration, one form which my invention may assume. In these drawings:

Figure 1 is a front elevation, with certain parts removed, of a refrigerator cabinet showing this illustrative form of my invention,

Figure 2 is a horizontal section through the brine tank taken on the line 2—2 of Figure 1 or Figure 3, while

Figure 3 is a vertical section through the brine tank taken on the line 3—3 of Figure 2.

In the drawings I have shown a refrigerator cabinet 11 comprising a cooling compartment 12, a supplemental refrigerated compartment 13 disposed below the cooling compartment 12, and a main refrigerated compartment 14 disposed beside the cooling compartment 12 and supplemental refrigerated compartment 13, the cooling compartment 12 being connected to the supplemental refrigerated compartment 13 by means of a passage 15, the supplemental refrigerated compartment 13 being connected to the main refrigerated compartment 14 by means of a passage 16, and the main refrigerated compartment 14 being connected to the cooling compartment 12 by means of a passage 17, all to permit flow of the circulatory air from the cooling compartment 12 through the passage 15 into the supplemental refrigerated compartment 13, through the passage 12 into the main refrigerated compartment 14, and through the passage 17 back into the cooling compartment 12.

Disposed within this cooling compartment 12 is a brine tank 18 comprising side walls

19, a front wall 20, a rear wall 21, a top 22, and a bottom 23, and comprising also a plurality of vertically aligned tubes 24 extending between the front wall 20 and the rear wall 21 and providing recesses 25 for the reception of trays 26 suitable for the production of artificial ice. Also positioned in the brine tank 11 is a suitable expansion unit 27 shown herein as comprising three coils 28 connected in series between the expansion valve 29 and the outlet 30 and each encircling one of the tubes 24.

In addition, the brine tank 18 herein shown comprises means to increase the area of contact between the brine and the circulatory air, this means being herein shown as two passages 31 extending vertically on either side of the tubes 24 between the top wall 22 and bottom 23 of the brine tank 18.

From the above description it will be obvious to those skilled in the art that the brine tank herein shown comprises passages extending in the general direction of flow of the circulatory air passing the brine tank 18, and arranged to permit the passage therethrough of a portion of the circulatory air to thus very greatly increase the area of contact between the brine within the brine tank 18 and the circulatory air transmitting the cooling effect of the brine throughout the refrigerator cabinet 11.

Under these circumstances it will be obvious to those skilled in the art that I have provided a new and improved brine tank particularly suitable for use in household and store installations.

At the same time it will also be obvious to those skilled in the art that the particular embodiment of my invention herein shown may be variously changed and modified without departing from the spirit of my invention or sacrificing the advantages thereof. It will therefore be understood that the disclosure herein is illustrative only and that my invention is not limited thereto.

I claim:

1. In combination, a refrigerator cabinet, and a brine tank located therein for cooling said cabinet by air convection, so positioned in said cabinet that the cooling air flows downwardly in passing said brine tank, provided with at least one recess extending into said brine tank from a lateral wall thereof and for the reception of a receptacle for the production of artificial ice, and provided also with at least one passage independent

of such recesses and extending through said brine tank in the general direction of the convection flow of the air in passing said brine tank, and expansion coil means located within said brine tank in closer proximity to said recess than to said passage.

2. In combination, a refrigerator cabinet, and a brine tank located therein for cooling said cabinet by air convection, so positioned in said cabinet that the cooling air flows downwardly in passing said brine tank, provided with at least one recess extending into said brine tank from a lateral wall thereof

and for the reception of a receptacle for the production of artificial ice, and provided also with two passages independent of such recesses and extending through said brine tank in the general direction of the convection flow of the air in passing said brine tank and disposed one on each side of such recesses, and expansion coil means located within said brine tank in closer proximity to said recess than to said passages.

In testimony whereof I hereunto affix my signature.

MAXWELL H. SPREEN.
